S. J. RAWLINGS

DOOR HOLDER

Filed Sept. 1, 1925

UNITED STATES PATENT OFFICE.

SAMUEL J. RAWLINGS, OF KEARNY, NEW JERSEY.

DOOR HOLDER.

Application filed September 1, 1925. Serial No. 53,913.

This invention relates to certain improvements in door holders and has relation more particularly to a device of this general character of an overhead type, and it is an object of the invention to provide a device of this kind which operates effectively to maintain the door in full open position or at other intermediate positions.

Furthermore, it is an object of the invention to provide a device of this kind comprising two pivotally connected sections, one of which being operatively engaged with a door and the other with the door frame or kindred support and wherein means is provided to prevent said sections from having relative movement beyond a center line when the door is at the limit of its opening movement.

The invention consists in the details of construction and in the combination and arrangement of the several parts of my improved door holder whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view partly in elevation and partly in section illustrating a door holder constructed in accordance with an embodiment of my invention and in applied position;

Figure 2 is a view partly in section and partly in top plan of the structure as illustrated in Figure 1;

Figure 3 is a fragmentary view in perspective illustrating the position of certain of the parts of the holder when the door is in open position;

Figure 4 is a view partly in top plan and partly in section showing the holder in position to maintain the door partly open;

Figure 5 is an enlarged fragmentary view partly in section and partly in elevation

of the pivoted end portions of the sections or arms of the holder;

Figure 6 is a view in bottom plan of the pivoted end portion of one of the arms or sections;

Figure 7 is a view in plan of the bushing comprised in the lock or latch mechanism herein comprised.

As disclosed in the accompanying drawings, my improved door holder comprises two sections or arms A and B of desired length and each having their outer extremities or end portions operatively engaged with the brackets 1 and 2 respectively, the bracket 1 being secured to the crown sill C of a door casing or the like while the bracket 2 is secured to the upper portion of the door D. The opposite or inner end portions of the arms A and B are provided with the circular plates or discs 3 in overlying relation and pivotally connected by a bolt 4 disposed through the axial centers thereof. By this means, the arms or sections A and B are connected for relative swinging movement and in order to prevent said arms when extended passing beyond a center, one of said arms, as B, is provided with an inwardly or upwardly disposed lip 5 positioned preferably immediately adjacent to a disc or plate 3 and with which is adapted to contact a suitably positioned angularly disposed lug 6 carried by the periphery of the disc or plate 3 of the arm A.

As herein set forth, the plate or disc 3 carried by the arm A is uppermost and the under surface of said plate or disc 3 is provided with an annular series of pockets or recesses 7 in which is adapted to be selectively engaged an end portion of a locking bolt 8. This bolt 8 has its working end portion disposed through a suitably positioned opening 9 provided in the plate 3 of the arm B and is extended outwardly through a tubular member or sleeve 10 depending from the disc or plate 3 of the arm B and preferably integrally formed therewith.

Threaded or otherwise engaged within the lower or free end portion of the member or sleeve 10 is a bushing 11 through

which the bolt 8 is directed, said bushing 11 serving as a guide for the bolt. Interposed between the inserted end of the bushing 11 and an outstanding collar 12 carried by the bolt 8 is an expansible member 14 herein disclosed as a coil spring encircling said bolt and which operates normally to urge the bolt 8 into working engagement with a pocket or recess 7, said collar 12 being arranged within the tubular member or sleeve 10.

As is particularly illustrated in Figure 7, the bore 15 of the bushing 11 has in communication therewith the diametrically opposed grooves 16 which are adapted to receive the oppositely directed outstanding projections 17 carried by the bolt 8 to permit said bolt to have desired movement for locking engagement with the plate or disc 20 3 of the arm A.

Through the instrumentality of the bolt 8 and the pockets or recesses 7, the door D may be effectively locked or held in its full open or closed position or at selective intermediate points.

The arms or sections A and B are normally locked against relative swinging movement but when it is desired to either open or close the door D, it is only required to 30 pull downwardly upon the bolt 8 until the projections 17 are free from the bushing 11 and then impose a slight rotary movement to the bolt 8 to bring such projections 17 out of register with the groove 16 in the bushing 11, the resultant contact of the projections 17 with the outer end of the bushing 11 holding the bolt 8 against return to locking or working position. It will also be understood that when it is desired to have 40 the arms or sections A and B free for relative swinging movement the bolt 8 will be maintained in such extended position.

In order to facilitate the desired operation

of the bolt 8, the outer or lower end portion thereof is provided with a cross handle 18 or its equivalent.

From the foregoing description it is thought to be obvious that a door holder constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

An overhead door hanger comprising a pair of arms, each of said arms having a plate at one end portion, the plate of one arm overlying the plate of the other arm, means for pivotally connecting said plates to permit the arms to have relative swinging movement, the inner face of one of the plates being provided with an annular series of 70 pockets, a bolt having movement through the second plate for a selective engagement with the pockets of the first plate to lock the arms against relative swinging movement, said bolt moving in a direction substantially parallel to the axis of the pivotal connection of the plates and extending downwardly from said plates, means for constantly urging the bolt toward the second plate for engagement within a pocket, and coacting 75 means carried by the bolt and the second plate for holding the bolt free from the first plate.

In testimony whereof I hereunto affix my signature.

SAMUEL J. RAWLINGS.
